UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

FLUID-APPLYING MACHINE.

1,376,524.

Specification of Letters Patent.

Patented May 3, 1921.

Application filed August 20, 1919. Serial No. 318,729.

To all whom it may concern:

Be it known that I, FREDERICK M. FURBER, a citizen of the United States, residing at Revere, in the county of Suffolk and State 5 of Massachusetts, have invented certain Improvements in Fluid-Applying Machines, of which the following description, in connection with the accompanying drawings, is a specification, like reference characters on 10 the drawings indicating like parts in the several figures.

The present invention relates to apparatus for applying fluids to various objects, it being particularly an improvement upon the 15 machine invented by me, and patented in my name on July 29, 1919, under the Number 1,311,161.

The above-mentioned apparatus is especially designed for the application of such 20 fluid stains as blacking to the edges of the soles of shoes, the fluid being sprayed from a nozzle against the work positioned horizontally beneath it by an edge-rest, preferably furnished by the supply conduit of the 25 machine, and positioned vertically with respect to its distance from the nozzle by a gage, which also serves as a guard to limit the application of the spray to the margin of the sole. It may be desirable to vary the 30 width of this coated margin, and for this purpose it has been suggested that there be mounted about the supply conduit an eccentric sleeve, against the surface of which the edge of the sole operated upon may bear, 35 the sleeve being adjusted as to angle to vary the projection of its wall beyond the conduit and therefore the distance of the work-guiding surface from the gage. Such an arrangement is not entirely satisfactory, 40 since, though the proper spacing may be obtained in one vertical plane, as directly opposite the nozzle, at each side of this the eccentricity will be different, and when the curved edge of the work is swung about 45 the rest by the operator as he advances it beneath the nozzle, the width of the coated area will vary with the angle. An object of the invention is to provide means in a machine of this character, by which the width 50 coated may be kept uniform regardless of the manner in which the work is moved over it. I accomplish this result by position- 55 varying means upon which the work-surface to be sprayed is held spaced from the spray-delivering means, this positioning means be-

ing movable in right lines toward and from the spray-delivering means and in a direction transverse to the spray delivery; the position-varying means or rest preferably maintains in its movement a symmetrical relation to the gage or guard previously mentioned. I have herein illustrated as a rest a tube surrounding the supply conduit and being spaced therefrom, this tube being mounted in a guide which determines its 60 movement of adjustment.

A further object of the invention is to effectively prevent the spray, especially after it has been broken up by contact with the work or guard, from being thrown into the 70 air to be wasted, or to cause injury by being inhaled by the operator or by settling upon surrounding objects. To this end, I have spray-retaining means extending from 75 a point adjacent to the spray-delivering means into proximity with the receptacle from which the fluid is drawn and toward which the spray is delivered. To this retaining means may be connected a suction conduit. The flying drops of fluid, too finely 80 divided to settle upon the body of fluid in the receptacle, are drawn off by the suction. The spray-retaining means preferably takes the form of a hood situated at the opposite side of the nozzle from the gage and partly 85 surrounding the work-rest.

In the accompanying drawing is shown a particular embodiment of the invention,

Figure 1 being a broken side elevation; and

Fig. 2, a perspective view of the elements 90 more closely connected with the present invention.

From a frame 10 projects an arm 12, in which is a passage delivering air under pressure to an outlet or blast tube 14 of an atomizing device carried by a head 16 supported at the outer extremity of the arm. Extending horizontally in the head is a mixing passage 18, to which is connected a supply 95 or suction conduit 20, shown as a vertical pipe mounted upon the head and extending into a receptacle 22 for the fluid which is to be applied. As the air current is discharged from the nozzle and through an opening 24 100 in the under side of the head alined with it, fluid is drawn, as is usual in atomizing devices, from the body contained within the receptacle through a strainer 26 mounted upon the lower extremity of the supply 110

pipe, it being here secured by a set-screw 28 threaded through a boss at its upper side. The fluid rising in the tube mingles with the air in the passage 18 and is ejected therefrom as a fine spray through the delivery opening. At the outer side of the opening 24 is a gage-plate 30 fixed to the head 16, preferably by a screw 32 extending through a vertical slot in the plate and being threaded into the head. When a sole the margin of which is to be blacked is placed with its upper face against the lower edge of this gage, the distance of the surface from the delivery opening is fixed, and drops of fluid deflected after contact with the work are retained by the gage, and their waste by falling upon central portions of the sole prevented. At the opposite side of the delivery opening from the gage is an edge-rest to position the work transversely of the path of the spray. This rest is preferably in the form of a tube or sleeve 34 surrounding the supply pipe 20 and extending from the head just below the opening 24 down to a support 36, which encircles the lower portion of the pipe 20 and conveniently rests upon the boss of the strainer 26, it being here secured in place by a set-screw 38 threaded through its wall and engaging the pipe. At the upper end of the support, at opposite sides of a horizontal contact surface, are guideways 40, 40 extending substantially at right angles to the inner work-engaging face of the gage 30 and equally spaced at opposite sides of the opening 24. In these ways is movably mounted a plate 42, to which the tube 34 is fixed. The support may be divided at one side, and through lugs adjacent to this division passes a screw 44, which may draw the walls of the support toward one another to clamp the plate 42 in its ways. The tube 34 is of greater internal diameter than the external diameter of the pipe 20 so that it is spaced therefrom. Consequently, when the screw 44 is loosened, the plate 42 may be slid in its ways to alter the distance between the gage-plate 30 and the adjacent side of the tube. There is, therefore, for such an adjustment a different marginal width of the sole inside the gage-plate subjected to the action of the spray, and, on account of the location of the ways with respect to the gage-plate and the delivery opening, the relation of the walls of the tube at opposite sides of the spray remains symmetrical, so that a sole turned in its advance, either in a clockwise or anti-clockwise direction about the rest, will receive a coating of the spray over the same width.

When the spray strikes the work and the inner face of the gage, the excess will be deflected in small drops, which, when thrown into the surrounding air, may be inhaled by the operator or float about the room and

cause damage. To prevent this in the machine hereinbefore mentioned, a conduit, through which a suction is maintained, has been connected to the upper wall 48 of the receptacle 22, this wall being inclined downwardly to a contracted central opening 50 about the supply pipe 20. It is found that though the heavier particles which would naturally be thrown down by gravity are effectively received by the opening 50, there is a considerable tendency for the finer misty portion, especially at the side away from the gage-plate or in the direction toward which the spray is deflected, to float beyond the receptacle so that it is not caught by the suction. To prevent this, spray-retaining means is placed at the opposite side of the supply pipe and work-rest tube from the gage-plate. This preferably consists of a hood 52, approximately semi-cylindrical in its horizontal contour and closed at the top by a portion 54 merging into the vertical wall by a curve 55. Connected to the hood is a suction conduit 56, which may also serve as a support for the hood. The suction through the conduit creates a current of air from the spray-applying area and at each side of the tube 34 within the hood 52. This may, by a proper strength of suction and positioning of the hood, be so proportioned that the fluid particles thrown off from the work and plate 30 will be to a great extent drawn into and temporarily retained by the hood 52, the heavier portion being precipitated upon the wall 48 of the receptacle and through the opening 50 to be taken up by the fluid body in the receptacle. A certain limited finer portion will be drawn into the conduit 56 and be carried off by the draft therethrough to be disposed of outside the room.

Having described my invention, what I claim as new and desire to secure by Letters Patent of the United States is:

1. In a machine of the class described, spray-delivering means spaced from the work surface to be sprayed, and means movable in right lines toward and from the spray-delivering means and arranged to vary the position of the work transversely to the direction of spray delivery.

2. In a machine of the class described, spray-delivering means, a gage situated at one side of the spray-delivering means, and a work-rest movable toward and from the gage and arranged to maintain a symmetrical relation in its movement to said gage.

3. In a machine of the class described, spray-delivering means, members for contact with the work at opposite sides of the spray-delivering means, and means arranged to vary symmetrically the relative positions of said members transversely to the direction of spray delivery.

4. In a machine of the class described, spray-delivering means, a guard for the work situated at one side of the spray-delivering means, and a work-rest situated at 5 the opposite side of the spray-delivering means from the guard and movable in right lines toward and from the guard. 15
5. In a machine of the class described, a fluid-applying device, a conduit delivering thereto, a work-rest surrounding the conduit and spaced therefrom to permit movement, and means arranged to fix the work rest against movement. 20
6. In a machine of the class described, a fluid-applying device, a conduit delivering thereto, and a work-rest mounted upon the conduit and being supported for movement symmetrically with respect to the fluid-applying device. 25
- 20 7. In a machine of the class described, a fluid-applying device, a conduit delivering thereto, a work-rest mounted upon the conduit and being supported for movement symmetrically with respect to the fluid-applying device, and means arranged to fix the rest in its symmetrical relation. 30
8. In a machine of the class described, a fluid-applying device, a conduit delivering thereto, a member for contact with the work surrounding and being spaced from the conduit, and means arranged to fix the member in different positions transversely of the conduit. 35
- 35 9. In a machine of the class described, a fluid-applying device, a conduit delivering thereto, guide means associated with the conduit, and a work-rest movable in the guide means and surrounding the conduit. 40
- 40 10. In a machine of the class described, a fluid-applying device, a conduit delivering thereto, guide means carried by the conduit, and a work-rest movable in the guide means. 45
- 45 11. In a machine of the class described, a fluid-applying device, a conduit delivering thereto, guide means associated with the conduit, and a tube surrounding the conduit and having a portion movable in the guide means. 50
- 55 12. In a machine of the class described, a fluid-applying device, a conduit delivering thereto, a support secured to the conduit, and a work-rest carried by the support. 60
- 60 13. In a machine of the class described, a fluid-applying device, a conduit delivering thereto, a support mounted adjacent to the conduit and provided with ways, and a work-rest movable in the ways. 65
14. In a machine of the class described, a fluid-applying device, a conduit delivering thereto, a support mounted adjacent to the conduit and provided with a clamp, and 65 a work-rest held by the clamp. 70
15. In a machine of the class described, spray-delivering means, a fluid receptacle from which the spray-delivering means is supplied and toward which the spray is delivered, and spray-retaining means extending from a point adjacent to the spray-delivering means into proximity with the receptacle. 75
16. In a machine of the class described, spray-delivering means, a suction conduit connected thereto and extending in the direction of spray delivery, and spray-retaining means extending from a point adjacent to the spray-delivering means toward the inlet of the suction conduit. 80
17. In a machine of the class described, spray-delivering means, a fluid receptacle, a conduit connecting the spray-delivering means and receptacle, and spray-retaining hood extending from a point adjacent to the spray-delivering means to the receptacle at the side toward the conduit, and being open at the opposite side for the application of work to the spray-delivering means. 85
- 90 18. In a machine of the class described, a spray nozzle, a work-guard situated at one side of the nozzle, and a hood situated at the opposite side of the nozzle. 95
19. In a machine of the class described, a spray nozzle, a work-guard situated at one side of the nozzle, a hood situated at the opposite side of the nozzle, and means for drawing spray from the hood. 100
20. In a machine of the class described, a spray nozzle, a work-rest extending from the nozzle and a hood partially surrounding the work-rest. 105
21. In a machine of the class described, a spray nozzle, a work-guard situated at one side of the nozzle, a work-rest situated at the opposite side of the nozzle, and a hood partially surrounding the work-rest. 110
22. In a machine of the class described, a spray nozzle, a receptacle arranged to supply the nozzle with the material to be sprayed and having a contracted opening, and a hood receiving spray from the nozzle and directing it to the receptacle opening. 115
23. In a machine of the class described, a spray nozzle, a receptacle arranged to supply the nozzle with the material to be sprayed and having a contracted opening, a hood receiving spray from the nozzle and directing it to the receptacle opening, and an outlet conduit leading from the hood. 120
24. In a machine of the class described, a spray nozzle, a receptacle having a contracted opening, a hood receiving spray from the nozzle and directing it to the receptacle opening, and a suction conduit connected to the hood. 125
25. In a machine of the class described, a receptacle having an upper wall in which is an opening, a pipe rising through the open- 130

4

ing, a nozzle to which the pipe delivers, and a hood partially surrounding the pipe and leading from the nozzle to the opening.

26. In a machine of the class described, a receptacle having an upper wall in which is an opening, a pipe rising through the opening, a nozzle to which the pipe delivers, a hood partially surrounding the pipe and leading from the nozzle to the opening, and 10 a suction conduit opening through the wall of the hood.

27. In a machine of the class described, a receptacle having an upper wall in which is an opening, a pipe rising through the opening, a nozzle to which the pipe delivers, a spray guard situated at the opposite side of 15

the nozzle from the pipe, and a spray hood situated at the opposite side of the pipe from the nozzle.

28. In a machine of the class described, a receptacle having an upper wall in which is an opening, a pipe rising through the opening, a nozzle to which the pipe delivers, a spray guard situated at the opposite side of the nozzle from the pipe, a spray hood situated at the opposite side of the pipe from the nozzle, and a suction conduit leading from and supporting the hood. 25

In testimony whereof I have signed my name to this specification.

FREDERICK M. FURBER.
